UNITED STATES PATENT OFFICE

HENRY FORD, OF DEARBORN, MICHIGAN, ASSIGNOR TO FORD MOTOR COMPANY, OF DEARBORN, MICHIGAN, A CORPORATION OF DELAWARE

PISTON FOR INTERNAL-COMBUSTION ENGINE

Application filed May 31, 1924. Serial No. 716,989.

The object of my invention is to provide new and useful improvements in a piston for internal combustion engines of simple, durable, and inexpensive construction.

5 A further object of my invention is to provide a piston which may be constructed from steel as distinguished from cast iron or aluminum. It will be understood that heretofore pistons for internal combustion engines have 10 ordinarily been made from cast iron but that such pistons are objectionable from the fact that the weight is very considerable and of course the effect of weight is much multiplied. in connection with a reciprocating part such 15 as a piston. It has been proposed to use aluminum and various other white metal alloys of relatively light weight for pistons and in fact a considerable number of such pistons have been used. Heretofore, however, such pistons have been objectionable 20 from the fact that their coefficient of expansion is much higher than the coefficient of expansion of the cast iron from which the cylinders are made, so that it is necessary to have 25 such pistons fit very loosely when the engine is cold in order that they may not bind when they expand from the heating of the engine after the engine has been in operation for some time. Such pistons, therefore, give 30 relatively poor compression and oil sealing at the time the engine is cold so that while they are more satisfactory from a weight standpoint, still they are not so satisfactory from other standpoints. It has also been 35 proposed to use steel pistons and I have been informed that a large number of expert engineers have attempted to solve the problem of using the steel piston as the steel would have substantially the same coefficient of ex- 40 pansion as the cast iron cylinder and yet the weight would be a fraction of that of the cast iron piston. A piston is a rather complicated construction due to the fact that it is necessary to provide relatively strong bosses to receive the sleeves which support the wrist pin 45 and it is also necessary to provide grooves for the piston rings and to brace the head so that it will not cave in or otherwise alter under the force of impact of the explosions in the 50 cylinder. Further, it is difficult to make the

skirt of a steel piston of sufficiently thin material so that it will be light enough and yet at the same time hold its circular shape.

With the foregoing explanation in mind, it is the further object of my invention to 55 provide a piston which may be formed from steel and which may have a sufficient rigidity in the skirt to keep it from losing its circular form, which may have sufficient material and rigidity in the dome to permit of the forming 60 of ring grooves and to withstand the shock of the explosions and which may have sufficient strength in the skirt and its connection with the dome so that bosses may be struck up to receive the wrist pin sleeves. 65

A further object of my invention is to so form the parts of my improved piston that they may be readily and satisfactorily welded together to withstand the necessary duties of 70 a piston.

A further object of my invention is to provide a piston having a forged head and a skirt of pressed steel of substantially tubular form which may be butt welded to the forged head.

A further object of my invention is to provide a skirt of substantially tubular form which may if desired be made initially in two halves which may be butt welded together. 75

A further object of my invention is to provide a sheet metal skirt of substantially 80 tubular form which may have ring grooves formed therein and bosses struck up therefrom to receive the wrist pin sleeves.

A further object of my invention is to provide bosses to receive the wrist pin sleeves 85 which are so arranged that a satisfactory welding job may be readily made in connection therewith.

With these and other objects in view, my invention consists in the arrangement, combination, and construction of the various parts of my improved device, as described in the specification, claimed in my claims, and shown in the accompanying drawings, in which: 90

Figure 1 shows a piston in elevation which has been constructed in accordance with my invention.

Figure 2 shows a bottom plan view of the piston illustrated in Figure 1. 100

Figure 3 shows a vertical-central sectional view taken on the line 3—3 of Figure 1.

Figure 4 shows a horizontal central sectional view taken on the line 4—4 of Figure 1, and Figures 5 to 14 inclusive show various schematic or diagrammatic views to illustrate the various steps in the formation of the sheet metal skirt for my improved piston. Figures 15 to 17 inclusive show a somewhat different method of securing the wrist pin sleeve in place on the wrist pin skirt.

I have used the reference character "A" to indicate the dome of a piston, the reference character "B" to indicate the skirt and the reference character "C" to indicate the boss struck up from the skirt to receive the wrist pin sleeve.

In the preferred form of my invention I form the dome "A" by forging same, the forging being a cup-shaped member as is indicated above the dotted line 10 in Figures 1 and 3. It will be seen that this forging may be readily forged out of a disc of steel in an ordinary forging machine. The ring grooves 11 are cut into the head "A" after it has been forged and of course they are suitably ground or otherwise shaped to the proper dimensions to receive the desired piston ring.

The skirt "B" of the piston is, as may be noted from the Figures 3 and 4 especially, of, generally speaking, tubular cylindrical form.

In Figures 5 to 14 inclusive I have illustrated one manner in which this skirt may be formed.

Referring to these figures it will be noted that in Figures 5, 6 and 7, I have illustrated an end, plan, and edge view, respectively of the blank from which one-half of the skirt may be formed. This blank may be placed in a suitable die so that it is formed to substantially semi-cylindrical form as is illustrated in the elevation plan and section of Figures 8, 9 and 10. It will be noted that this blank has an opening 12 formed therein by this operation which forms the pilot opening for the punch which latter will form the boss in the blank to receive the wrist pin sleeve. The blank also has a ring receiving groove 13 formed near the bottom edge thereof and a stiffening rib 14 formed at the bottom thereof by this same operation. Adjacent to the lower edge of the ring groove 13 I provide a struck in portion 15 which terminates in a flange 16 at the lower edge of the ring groove 13 whereby I perform the double function of strengthening the skirt to keep it round and of forming a combined flange and groove for wiping the oil from the surface of a cylinder. When the blank has been formed, as shown in Figures 8, 9 and 10, it is then again placed in a press and the wrist pin receiving boss 17, illustrated in Figures 11 and 12 is struck up, the pilot opening 12 being used to locate the punch member which

forms the boss 17 and to permit the edge of the boss to be relatively smooth and unbroken. This wrist pin receiving boss is of substantially cylindrical section in all vertical planes and straight section in all horizontal planes. After the boss has been struck up, as illustrated in Figures 11 and 12 then the wrist pin receiving sleeve 18 is forced into the boss with a press fit. In order to be sure that there is no play between the sleeve 18 and the boss 17, I prefer to use a pencil arc weld or line weld at 19 and 20 to further secure the boss and sleeve together. After this has been accomplished a pair of the skirt sections, such as is shown in Figure 13, are placed with their lateral edges together and these lateral edges butt welded together at 20 to form the tubular skirt illustrated in the plan view in Figure 14.

It is possible to form a skirt heretofore described by drawing same from a single perforated disc or tube to tubular form and then striking up the bosses and ring grooves and reinforcing flanges or ribs after the member has been so drawn.

The skirt "B" when formed, as heretofore described is then butt welded on the dotted line 10 to the dome "A" so that the piston has the form when completed as illustrated in Figures 1 to 4 inclusive.

The form of device illustrated in Figures 15 to 17 inclusive shows a different method of securing the wrist pin sleeve in place. Here the skirt is perforated or punched and then dished inwardly while the sleeve is formed with an up-set outwardly extending flange intermediate of its ends, which is butt welded to the edges of the perforation in the disc portion of the skirt. It will be noted that the dished in portion may be said to be of conical shape and the up-set flange on the sleeve is also of somewhat conical shape so that when these parts are forced together in the presence of a welding current then the heating of the metal will break the metal down so that a continuous weld or joint between the two parts will be insured.

Many advantages arise from the use of my improved piston and among these advantages it should first be pointed out that the piston here described is thoroughly practical as it has actually been made and run on test in engines with thoroughly satisfactory results. Further, the weight of the piston is very small as compared with that of the cast iron piston so that the well known advantages of a light weight piston are secured by using the construction herein disclosed without the disadvantages of the light weight pistons which have heretofore been used with regard to the fitting of the cylinder under various engine conditions.

Another advantage resulting from the use of this improved piston is that it may be relatively cheaply manufactured and that the

manufacturing operations are of themselves of such a nature that they may be readily adapted for cheap and large production.

I claim as my invention:

1. A piston for internal combustion engines having a forged head with ring grooves therein, a cylindrical sheet metal skirt integrally united with said forged head, said skirt having a pair of diametrically opposite dished in portions formed therein, a pair of wrist pin receiving sleeves, and radial flanges extending from substantially the longitudinal center of each sleeve, the flanges being integrally united with the adjacent inner edges of the dished in portions to form a unitary structure.

2. A piston for internal combustion engines having a forged head, said head having a ring groove formed therein, a sheet metal skirt, said skirt being integrally united with the head and being formed with opposite transverse dished in portions having an opening formed at substantially the middle part thereof, a pair of wrist pin receiving sleeves, and radially extending flanges disposed substantially at the longitudinal center of said sleeves, said flanges being integrally united with the edges of the openings in said dished in portions of the skirt.

HENRY FORD.
